VARIABLE ATTENUATOR

Ernst Weber, Mount Vernon, and Stanley A. Johnson, New York, N. Y., assignors to Polytechnic Institute of Brooklyn, Brooklyn, N. Y., a corporation of New York

Application June 21, 1945, Serial No. 600,726

21 Claims. (Cl. 178—44)

1

This invention relates to variable attenuators for high frequency currents and especially for currents having frequencies in the ultra-high frequency range and higher.

For many applications in laboratory measurements as well as in test equipment in the field, it is necessary to have variable attenuators available in order to measure power output of tubes as oscillators, to regulate the power flow into special equipment, and for other purposes.

An object of the invention is to devise a variable attenuator for high frequency currents and having a broad band characteristic.

A further object of the invention is to devise a variable attenuator in which good matching is obtained in all positions of adjustment and in which there is a very low minimum value of attenuation or low insertion loss.

Still another object of the invention is to devise a variable attenuator in which there is symmetry with respect to matching at all positions of adjustment. In other words, for all adjustments of the attenuator, the matching is substantially the same for either direction of transmission through the attenuator.

Broadly the invention involves a transmission conductor having an attenuator section of relatively high resistance providing the necessary maximum attenuation. The high resistance section is formed with a wall thickness preferably less than the depth of penetration (skin depth). A shunting sleeve surrounds the conductor and is slideable along the conductor to effectively shunt out a variable portion of the attenuator section. For the purpose of effecting matching of the attenuator for all positions of adjustment of the sleeve, the attenuator section of the conductor is provided with a matching section at one end thereof, and the shunting sleeve is provided with a similar matching section arranged so that the effective portion of the attenuator lies between said matching sections in all positions of adjustment of the shunting sleeve.

Different embodiments of the invention are illustrated in the accompanying drawing in which:

Figure 1 is a plan view showing one construction of a variable attenuator formed as a unitary assembly adapted to be inserted in a coaxial line;

Figure 2 is a longitudinal sectional view of the arrangement shown in Figure 1 along the line 2—2;

2

Figure 3 is a longitudinal sectional view showing a modified form of shunting sleeve which may be used in the arrangement of Figure 2; and

5 Figure 4 is a longitudinal sectional view of a modified arrangement where the variable shunting element is operated by a member extending out of a mounting stub positioned at a right-angle bend in the cable.

10 Referring to Figures 1 and 2, the attenuator is embodied in a unitary assembly which may be inserted in a coaxial line. The attenuator unit is mounted within a cylindrical casing formed of two tubular sections 1a and 1b joined

15 together by a suitable coupling 1c. The attenuator unit 2 is mounted at the center of the casing and forms a linear section of the center conductor of a coaxial cable. This unit is formed of an insulating tube or rod having bullet-type connectors 2a and 2b at the ends thereof which engage sockets formed in the ends of center conductor connectors 3a and 3b mounted in the two sections of the attenuator casing.

20 Connectors 3a and 3b are supported within the casing by means of quarter-wave stubs 3a' and 3b'.

25 A thin metallic film is deposited on the outer surface of the insulating tube to provide the required attenuation in the current transmitted

30 through the attenuator assembly. The attenuator film is very thin, preferably only a fraction of the depth of penetration (skin depth), although greater thicknesses may be used up to twice the depth of penetration. As shown in Figure 2, the

35 film on the insulating tube of the attenuator unit 2 is divided into various sections marked by the points a, b, c, d, and e. The active attenuator film of small thickness is located in the section between the points c and d. The film in the sec-

40 tion b—c is thicker than the section c—d and comprises a transformer section or matching section to prevent or cancel wave reflections produced by the attenuator section c—d. The film section a—b is relatively thick and is equivalent to a solid metal conductor. Likewise, the film section d—e is relatively thick and is equivalent to a solid conductor.

45 A shunting sleeve is mounted to slide on the attenuator unit 2, and in the arrangement shown in Figure 2, this sleeve is formed of a metallic section 4 having an insulating section 5 joined thereto. The metallic sleeve 4 is formed of very thin wall thickness consistent with mechanical

50 requirements in order to take up as little space

as possible. It is also desirable that the insulating sleeve section 5 be as thin as possible. Between the points 5a and 5b on the insulating section 5, a thin metallic film is formed on the inner wall of the insulating tube, and this film serves as a matching section equivalent to the matching section b—c on the attenuator unit 2. Generally speaking, the matching section 5a—5b on the shunting sleeve will be of the same length as the matching section b—c on the attenuator unit. A thicker film equivalent to a solid conductor is placed on the inner wall of the insulating section 5 between the point 5b and the end of the metallic section 4 indicated at 4b, and this thick film has electrical connection with the metallic section 4 so that the shunting sleeve between the points 4a and 5b is equivalent to a solid metallic sleeve. If desired, the metallic sleeve 4 may be made of the proper length to form the entire section 4a—5b. This section should be sufficiently long to bridge the portion of the attenuator unit 2 between the points b and d; in other words, the section 4a—5b of the shunting sleeve should have a length equal to or greater than the combined length of the sections b—c and c—d of the attenuator unit 2. As shown in Figure 2, the section 4a—5b of the shunting sleeve is slightly longer than the combined sections b—d of the attenuator unit and the sleeve is in a position to bridge the active film section and the transformer section of the attenuator unit. This is the position of the shunting sleeve for lowest attenuation.

The distance A between the end of the metallic sleeve 4 and the end of the mounting 3b should be long enough to permit the shunting sleeve to be moved to the right until the point 5b on the sleeve comes opposite the point d on the attenuator unit 2. This would be the position of the shunting sleeve for producing maximum attenuation with substantially equal matching in both directions of transmission. In this position of the sleeve, the end of the transformer section on the shunting sleeve would be at the point 5a', and the active attenuator film section would then be located between the point c and the point 5a'. As the shunting sleeve is moved from this position towards the left, more and more of the active attenuator film is shunted out by the shunting sleeve and the attenuation is reduced accordingly. When the shunting sleeve reaches the position shown in Figure 2, the entire active section of the attenuator film, as well as the transformer section b—c, is bridged by the solid shunting portion of the shunting sleeve, and the attenuation is at a minimum. With this position of the sleeve, the transformer section 5a—5b of the shunting sleeve surrounds the section a—b of the attenuator unit and has no substantial effect.

The present invention is not concerned with a method of forming the different metallic films embodied in the attenuator unit and in the shunting sleeve, but we prefer to form these films of an alloy of at least two noble metals, the alloy having substantially zero temperature coefficient. For the purpose of preventing mechanical injury to the various films by the sliding of the shunting sleeve over the attenuator unit, the films should be coated with a suitable varnish to prevent direct contact between relatively movable metallic surfaces.

For the purpose of adjusting the position of

the shunting sleeve of the attenuator unit, a handle 6 of insulating material is secured to the sleeve 4 and extends radially out of the casing through a longitudinal slot formed therein. A rack 7 is mounted outside of a casing 1a and one end thereof is connected with the handle 6 by means of a suitable connecting element 7a. The rack may be mounted in various ways for sliding movement parallel with the axis of the attenuator unit 2, and one suitable arrangement is illustrated in Figures 1 and 2 where the rack 7 passes through an aperture formed in a block 8 which is rigidly mounted on the casing section 1a. A pinion 9 is mounted within a cavity formed in the block 8 and engages the rack 7, the pinion being mounted on a shaft 9a which is journaled in the block 8 and is provided with an operating knob 10. Thus, by turning the knob 10, the rack may be driven in either direction to adjust the position of the shunting sleeve on the attenuator unit 2.

A suitable pointer 11 may be attached to the rack 7 and arranged to cooperate with a graduated scale 12 formed on the surface of casing section 1a along the path of travel of the pointer 11.

The rack 7 and the handle 6 may be protected from mechanical injury and interference by arranging guard strips 13a and 13b on each side of the block 8 and over the path of travel of the rack 7 and the handle 6. The outer ends of these guard strips are supported by suitable blocks 13c and 13d.

An adjustable stop may be provided to limit the travel of the rack 7 and may be formed of a screw 14 having threaded engagement with the block 13c and arranged in line with the end of the rack 7. A locknut 14a is provided to hold the screw in any position of adjustment.

Figure 3 shows a modified form of the shunting sleeve in which the entire sleeve is formed of a single insulating sleeve 5' having a metal film covering the entire inner surface throughout its length. The film between the points 4a and 5b is made relatively thick and is equivalent to a solid metal sleeve, while the film covering the transformer section 5a—5b is a thin film having the necessary resistance to secure the desired matching between the solid film section and the active attenuator film section on the attenuator unit 2. The shunting sleeve of Figure 3 functions in the same manner as the sleeve of Figure 2.

In Figure 4 we have shown a modified arrangement for mounting the attenuator unit and for varying the position of the shunting sleeve. In this arrangement, 1 is the outer tubular conductor of a coaxial cable, and 1' is a section of the cable after making a right-angle turn. The attenuator unit 2 is mounted concentrically with 60 in the section 1' of the cable, the right end of the unit being supported in any suitable manner, such as by the use of a bullet type of connector as shown in Figure 2 and is connected with the center conductor of the cable. The left 65 end of the attenuator unit extends through a bore formed in a tubular support 3c which is supported in the end of cable section 1 by a suitable plug 1d. The outgoing center conductor 3c' is connected to the sleeve 3c at a point substantially one-quarter wave length from the inner face of plug 1d.

The shunting sleeve surrounding the attenuator unit 2 is formed substantially like the shunting sleeve of Figure 2 and consists of a metal sleeve 4 which passes through the bore of sleeve

3c and extends to the outside of the cable where it may be manually adjusted in position, and an insulating sleeve 5 is attached to the inner end of the metal sleeve 4 and carries the transformer section of the shunting sleeve. This transformer section is formed in the same manner as in Figure 2 and comprises a thin metallic film formed on the inner surface of the sleeve 5. It will be understood that the attenuator unit 2 is provided with a matching section near its right-hand end corresponding to the matching section b—c in Figure 2. If desired, a suitable rack and pinion arrangement may be provided for adjusting the sleeve 4 to various positions on the attenuator unit 2.

From the description of the operation of Figure 2, the operation of Figure 4 will be obvious, since movement of the shunting sleeve will be effective in shunting out a variable portion of the effective section of the attenuator unit 2.

We claim:

1. A variable attenuator for a coaxial cable comprising an inner transmission conductor of said cable having an attenuator section of relatively high resistance interposed between two relatively fixed low-resistance sections of said conductor and providing the necessary maximum attenuation, and a conductive sleeve surrounding said conductor and being slideable along said conductor to effectively shunt a variable portion of said attenuator section.

2. A variable attenuator according to claim 1 wherein said attenuator section is formed as a tubular conductor having a wall thickness less than twice the depth of penetration.

3. A variable attenuator comprising a tubular conductor having an attenuator section of high resistance interposed between two relatively fixed terminal sections of low resistance, and a low resistance sleeve surrounding said conductor and being slideable along said conductor to effectively shunt a variable portion of said attenuator section.

4. A variable attenuator structure comprising a tubular casing, a conductor having a low resistance tubular section joined to a high resistance tubular section of the same diameter, a conductive sleeve surrounding said low resistance tubular section and being movable along said conductor to surround said high resistance tubular section, and means for effecting movement of said sleeve from outside of said casing.

5. A variable attenuator comprising a tubular conductor having an attenuator section of high resistance interposed between two relatively fixed terminal sections of low resistance, a low resistance sleeve surrounding one of said terminal sections, a matching section interposed between the other terminal section and said attenuator section, and a tubular matching section carried on the end of said sleeve nearest said first-mentioned matching section, said sleeve and the attached matching section being movable along said conductor to surround a variable length of said attenuator section.

6. A variable attenuator comprising an insulating carrier, a thin metallic film formed on an intermediate section of said carrier, relatively thick metallic films formed on the terminal portions of said carrier and connected with said thin film, a conductive sleeve surrounding said carrier and being movable along said carrier to effectively shunt a variable portion of said thin film.

7. A variable attenuator according to claim 6

and including a matching section of film interposed between one terminal portion and said thin film on said carrier, and a matching section located at one end of said conductive sleeve.

8. A variable attenuator structure comprising, in combination, a tubular casing, a center conductor mounted within said casing and embodying an attenuator section of relatively high resistance, a sleeve of conductive material surrounding said center conductor and being movable into position surrounding said attenuator section, and means extending outside of said casing for effecting movement of said sleeve along said conductor.

9. A variable attenuator structure comprising, in combination, an outer tubular casing having a slot formed therein parallel with its axis, a center conductor mounted within said casing and embodying an attenuator section, a conductive sleeve surrounding said inner conductor and being movable into position to surround said attenuator section, and operating means secured to said sleeve and extending through said slot to the outside of said casing.

10. A variable attenuator according to claim 9 and including a rack mounted on said casing for sliding movement parallel with the axis thereof, and a pinion for operating said rack, and a pointer carried by said rack and cooperating with an indicating scale carried by said casing.

11. A variable attenuator structure comprising, in combination, an outer casing having two sections arranged at right angles to each other, a center conductor arranged within said casing, a quarter wave support for supporting said inner conductor at the bend in said casing, said support having a bore formed in alignment with one section of said inner conductor, an attenuator unit embodied in said one section of inner conductor, and a conducting sleeve positioned within said bore and surrounding said one section of inner conductor, said sleeve being movable in said bore to effectively shunt a variable portion of said attenuator unit.

12. An attenuator comprising a concentric transmission line and consisting of a tubular outer conductor and a centrally disposed inner conductor, said inner conductor consisting of two separated sections of low resistance, a member bridging the gap between the separated ends of said sections and serving to attenuate waves transmitted between said low resistance sections, and a conductive sleeve surrounding said inner conductor and being adjustable along said inner conductor to surround an adjustable portion of said attenuating member.

13. An attenuator according to claim 12 wherein said attenuating member is formed of a dielectric carrier provided with a high resistance coating on the surface thereof.

14. An attenuator comprising a concentric transmission line and consisting of a tubular outer conductor and a centrally disposed inner conductor, said inner conductor consisting of two separated sections of low resistance and a conductive sleeve closely surrounding one section of said inner conductor and being adjustable in position along said inner conductor to vary the gap between one end of said sleeve and the end of the other low resistance section of the inner conductor.

15. An attenuator according to claim 14 and including a rod of dielectric material interposed between the separated sections of inner conduc-

tor and having substantially the same outside diameter as said inner conductor.

16. An attenuator according to claim 15 wherein said dielectric rod is provided with a high resistance coating on the surface thereof.

17. A loss-producing variable attenuator for high frequency currents comprising a high resistance conductor section having a wall thickness less than twice the depth of penetration of said currents, and a conductive shunting member arranged in closely spaced relation to said conductor section but out of contact therewith and being movable parallel therewith to provide a transmission path in parallel with a variable portion of said conductor section.

18. An attenuator structure for a coaxial cable having a tubular outer conductor and a center conductor, the combination of an effective quarter-wave stub mounting for supporting said center conductor, a variable attenuator unit arranged within said outer conductor and having a movable element for varying the attenuation thereof, and means located within the center support of said stub mounting and extending out of the end of said mounting for adjusting the position of said movable element.

19. In a coaxial cable construction, the combination of a tubular outer conductor and a center conductor, an effective quarter-wave stub mounting for supporting said center conductor within said outer conductor, a movable element enclosed within said tubular conductor for varying the transmission characteristic of said cable, and means located within the center support of said stub mounting and extending out of the end of said mounting for adjusting the position of said, movable element.

20. A variable attenuator for high frequency currents comprising a low resistance transmission conductor having a high resistance section interposed between two low resistance sections, 5 a matching section of lower resistance than said high resistance section interposed between said high resistance section and one of said low resistance sections, the wall thickness of said high resistance section being less than twice the depth 10 of penetration, and a conductive shunting member arranged in closely spaced relation to the other low resistance conductor section but out of contact therewith and being movable into closely spaced relation with said high resistance section 15 to provide a transmission path in parallel with a variable portion of said high resistance section.

21. A variable attenuator according to claim 20 wherein said shunting member is provided with means at the end thereof for preventing wave reflection.
